[57] CLAIM

The ornamental design for a fishing lure, or similar article as shown and described.

DESCRIPTION

FIG. 1 is a perspective view of the invention;
FIG. 2 is a front elevational view of the invention;
FIG. 3 is a side elevational view of the right side of the invention;

FIG. 4 is a side elevational view of the left side of the invention;

FIG. 5 is a back elevational view of the invention;
FIG. 6 is a top plan view of the invention; and

FIG. 7 is a bottom plan view of the invention.
The hook disclosed in dotted lines in the several views is shown for illustrative purposes only and form no part of the claimed design.

FIG. 1

FIG. 2

FIG. 3

FIG. 4

FIG. 5

FIG. 6

FIG. 7
